UNITED STATES PATENT OFFICE.

OTTO FERDINAND MAYER, OF BERLIN, GERMANY.

TYPE-WRITING MACHINE.

SPECIFICATION forming part of Letters Patent No. 634,988, dated October 17, 1899.

Application filed May 24, 1898. Serial No. 681,640. (No model.)

To all whom it may concern:

Be it known that I, OTTO FERDINAND MAYER, a subject of the King of Prussia, German Emperor, residing at Berlin, in the Kingdom of Prussia, German Empire, have invented certain new and useful Improvements in Type-Writing Machines, of which the following is a specification.

This invention refers to type-writing machines of the kind in which the types are located upon a rotary type-wheel; and my invention relates to certain arrangements and combinations of parts by means of which the movements of the keys are transmitted to the type-wheel, so as to properly adjust the latter.

In order to make my invention more clear, I refer to the accompanying two sheets of drawings, in which similar letters denote similar parts throughout the several views, and

20 in which--

Figure 1 is a plan of the machine, some of the keys and the rear parts of the machine being broken away. Fig. 2 is a section in line xx of Fig. 1, and Fig. 3 is a section in line yy of Fig. 1 and drawn on a slightly larger scale.

The keys a are secured to double-armed levers b , arranged upon a common axle c . The rear end of each lever is bent in such a manner as to form a kind of a rather long U , (see d , Figs. 1 and 2,) having a curved middle part and two short horizontal end parts, one of which connects the U or the part d with the respective key-lever b . All these horizontal U 's open either to the right or to the left or partly to the right and partly to the left, (see Fig. 1,) and all the curved middle parts of them or the parts d take over an axle or shaft f , having secured to it as many wedge-like 40 disks or frames l as there are levers b in the machine. In view of the somewhat fork-like configuration of the parts d aforescribed I will call these parts "forks" in the further course of this specification. The positions of said frames l upon the shaft f are different, as are also the positions of the forks d with regard to said frames, the arrangement being such that the shaft f is turned in one or the other direction when one of said frames is acted on by the respective fork, the angle of movement of said shaft being, however, in any case a different and distinct one. The type-wheel

i is located above the shaft f . The axle of the type-wheel is provided with a bevel-wheel h , which gears with a bevel-wheel or beveled sector g , secured to the shaft f . Each rotation or part of a rotation of the latter results, therefore, in a corresponding movement or rotation of the type-wheel i , and as the angle of rotation is a special or distinct one in any single case or with regard to any single key, respectively, the type-wheel is adjusted to print the desired letter when the key bearing that letter is depressed.

A rod k , located in the front part of the machine, extends along immediately below all the key-levers and is connected by links l with the axle c of said levers. The middle part of said rod is connected by a link m with a rod n , extending through the base of the machine, to the rear of the latter, and being connected at the point o to the shorter arm of a double-armed lever p , forming at its longer arm a hammer r .

q is the fulcrum of the hammer-lever p . The latter is actuated when any of the keys a is depressed, and the paper is thereby struck against the type-wheel, so that the respective type is imprinted upon the same. The hammer then returns to its former or original position in consequence of its own weight, and in doing so it tends to raise the respective key, which is also raised by the greater weight of the rear arm of its respective lever. Of course the ascension of the keys and the return movement of the other parts may be effected or facilitated by springs; but it is just an advantage in my improved machine that I may dispense with the use of such auxiliary means and may thus not only simplify the construction, but also facilitate the practical use of the machine, as the operator need neither overcome the increasing tension of springs nor regulate or change such ones.

The types may be arranged upon the type-wheel i in two or more series or circles located in known manner one over the other. To raise the type-wheel, together with its axle, or along upon the same, so as to bring another series of types in proper position with regard to the hammer r , I make use of two levers u , (if the types form three series,) having each a key t and being located upon the axle c . This arrangement, however, is known, and I do

not lay a claim thereon, as is also the case with the means for transporting the paper-roller for the purpose of effecting the spacing and with the means for inking the types.

5 Owing to all these mechanisms being known, I have dispensed with fully representing and describing the same.

v is the key for effecting the spacing. This key may well be replaced by a ledge extending in known manner along the front side of the machine, and the two keys *t* may well be located at the sides of the machine instead of in the middle part of the same.

A particular feature of my invention resides in the fact that the type-wheel does not return to an original or normal position after each actuation, but remains after an adjustment in that respective position until another key is depressed. This is an important point, 20 as the power to be applied in operating the machine is also hereby remarkably reduced.

In the whole, my improved machine combines facility of operation with simplicity of construction. The adjustment of the types 25 occurs easily and securely, and the price of manufacture is a very moderate one.

Having now described my invention, what I desire to secure by Letters Patent of the United States is—

In a type-writing machine having a rotary type-wheel that remains at rest after each actuation, the combination with said type-wheel, a horizontal rocking shaft, and means for transmitting the oscillatory movements of said shaft to the type-wheel, of wedge-like parts *e* secured in different positions to said shaft and having their broader parts located above their smaller ones; fork-like parts *d* taking laterally below the broader parts of said wedges, so as to lie between these parts 40 and the shaft, levers *b* having said forks attached to them, and keys attached to the other ends of said levers, for the purpose as described.

In witness whereof I have hereunto signed 45 my name, this 12th day of May, 1898, in the presence of two subscribing witnesses.

OTTO FERDINAND MAYER.

Witnesses:

C. H. DAY,
HENRY HASPER.
